(57) CLAIM

The ornamental design for a bassinet, as shown and described.

DESCRIPTION

FIG. 1 is a left elevational view of the design for a bassinet of the present invention, with the shoulder strap shown extending below the bassinet;

FIG. 2 is a right elevational view of the bassinet of FIG. 1;

FIG. 3 is a front elevational view of the bassinet of FIG. 1;

FIG. 4 is a back elevational view of the bassinet of FIG. 1; and,

FIG. 5 is a perspective view of the bassinet of the present invention, with the shoulder strap shown extending to the rear of the bassinet.

The broken lines illustrated in the drawings form no part of the design.
